UNITED STATES PATENT OFFICE.

FLOYD T. ROMBERGER, OF ELIZABETHVILLE, PENNSYLVANIA.

INTERNAL-COMBUSTION ENGINE.

1,152,763.

Specification of Letters Patent.

Patented Sept. 7, 1915.

Application filed June 21, 1915. Serial No. 35,377.

To all whom it may concern:

Be it known that I, FLOYD T. ROMBERGER, a citizen of the United States, residing at Elizabethville, in the county of Dauphin and State of Pennsylvania, have invented 5 certain new and useful Improvements in Internal-Combustion Engines, of which the following is a specification.

My invention relates to improvements in 10 internal combustion engines of the general type which embody rotary valves.

An important object of the invention is 15 to provide means whereby the rotary valve will not bind, leak, or be liable to derangements.

Other objects and advantages of the invention will be apparent during the course 20 of the following description.

In the accompanying drawings forming 25 a part of this specification and in which like numerals are employed to designate like parts throughout the same, Figure 1 is a central vertical longitudinal sectional view through a valve embodying the invention, taken on line 1—1 of Fig. 2, Fig. 2 is a transverse sectional view taken on line 2—2 of Fig. 1, Fig. 3 is a side elevation of valve-sleeve 30 operating means, and, Fig. 4 is a side elevation of a cam and associated elements embodied in the operating means.

In the drawings, wherein for the purpose 35 of illustration is shown a preferred embodiment of my invention, the numeral 5 designates the cylinders of an internal combustion engine, having a head or casting 6. This head or casting is provided with laterally spaced longitudinal bores 7, receiving tubular valves and valve-sleeves, to be described. The head or casting 6 is provided 40 with openings for receiving spark plugs 8, arranged as shown.

Each bore 7 in the head or casting 6 is 45 cylindrical and adapted to communicate with the interior of the cylinders. Rotatably mounted within each bore 7 is a thin outer valve-sleeve 9, the exterior surface of which is cylindrical, while its bore is tapered. This outer valve sleeve is split longitudinally throughout its entire length, as 50 shown at 9¹, whereby it is circumferentially contractible and expansible. Arranged within the outer valve sleeve 9 is an inner valve sleeve 10, having a longitudinally tapered exterior surface while its bore is cylindrical. 55 This inner valve sleeve is also thin and split longitudinally throughout its entire length,

as shown at 10¹, whereby it is circumferentially expandible and contractible. The splits or openings 9¹ and 10¹ are arranged to permanently break-joint, whereby all leakage is prevented. Surrounding the opposite ends of these valve-sleeves are compressible coil springs 11, contacting with flanges 11¹ carried by the valve-sleeves, to move them inwardly in opposite directions, whereby 60 their beveled contacting faces have proper engagement.

Rotatably mounted within each inner valve-sleeve 10 is a cylindrical tubular valve 12, provided with suitable ports 13, for 65 movement into and out of registration with enlarged ports 14. These enlarged ports are formed in the valve-sleeves and remain permanently in registration, as the valve-sleeves are not turned sufficiently with relation to 70 each other to cause these ports to be moved completely out of registration.

Means are provided to slightly turn the valve-sleeves 9 and 10, comprising cranks 75 15, which are secured to the ends of the valve-sleeves, projecting outwardly beyond the ends of the head or casing 6. Pivots connected with each crank 15 is a pitman 16, extending downwardly for pivotal connection with an eccentric strap 17, slidably 80 mounted upon an eccentric 18, in turn mounted upon a shaft 19. This shaft may be the crank-shaft of the engine, or a shaft driven by it.

The tubular valve receives its rotation 85 from a sprocket wheel 20, mounted thereon, and engaged by a sprocket chain 21, engaging a sprocket wheel 22. This sprocket wheel is rigidly mounted upon the shaft 19. Having a swiveled connection with the opposite end of each tubular valve is a pipe 23, adapted to serve as an inlet or exhaust pipe.

In Fig. 2, I have shown the engine as embodying two tubular valves, one of which is 90 an inlet valve and the other an exhaust valve. Instead of employing two of these valves it is obvious that by properly arranging the ports therein, a single valve may be 95 employed to operate the inlet and exhaust 100 of gases to and from the cylinders. It is also obvious that instead of employing a tubular valve, a solid rotary valve, with suitable ports, may be employed. In the operation of each valve, it is continuously rotated, for bringing its ports into and out 105 of registration with the ports 14 in the 110

valve-sleeves. The pressure of the springs 11 upon the flanges 11¹, move the valve-sleeves inwardly longitudinally, and by virtue of their tapered contacting faces, the 5 inner valve-sleeve is contracted to properly slidably contact with the tubular valve for preventing leaks and the like, while the outer tubular valve-sleeve is expanded to properly contact with the wall of the bore 10 7, preventing leakage. In order that these circumferentially expansible valve-sleeves may not bind or freeze, whereby they could not properly operate, such valve-sleeves are slightly turned back and forth, during the 15 operation of the engine. Such action is effected by the cams 18 and associated elements.

It is to be understood that the form of my invention herewith shown and described is 20 to be taken as a preferred example of the same, and that various changes in the shape, size, and arrangement of parts may be resorted to without departing from the spirit of the invention or the scope of the sub- 25 joined claims.

Having thus described the invention, I claim:

1. The combination with an engine having a valve casing, of a rotatable valve arranged within the valve casing, a pair of telescoping valve-sleeves disposed between

the valve casing and the valve and having tapered contacting surfaces, and yielding means to move one valve-sleeve longitudinally in one direction.

2. The combination with an engine having a valve casing, of a rotatable valve arranged within the valve casing, a pair of telescoping valve-sleeves disposed between the valve casing and the valve and having tapered contacting surfaces, yielding means to move the valve-sleeves inwardly longitudinally, and means to effect a relative turning movement between the valve-sleeves.

3. The combination with an engine having a valve casing, of a rotatable valve arranged within the valve casing, a pair of telescoping longitudinally split circumferentially expansible and contractible valve-sleeves disposed between the valve casing and valve and having tapered contacting surfaces, yielding means to move one valve-sleeve longitudinally with relation to the other, and means to effect a relative turning movement between the valve sleeves.

In testimony whereof I affix my signature in presence of two witnesses.

FLOYD T. ROMBERGER, M. D.
